CLAIM

The ornamental design for a grill weight, as shown and described.

DESCRIPTION

FIG. 1 is a perspective view of a first embodiment of a grill weight showing my new design.

FIG. 2 is a front view thereof.

FIG. 3 is a bottom view thereof.

FIG. 4 is a top view thereof.

FIG. 5 is a left side view thereof.

FIG. 6 is a right side view thereof.

FIG. 7 is a rear view thereof.

FIG. 8 is a perspective view of a second embodiment of the grill weight of FIG. 1.

FIG. 9 is a front view thereof.

FIG. 10 is a bottom view thereof.

FIG. 11 is a top view thereof.

FIG. 12 is a left side view thereof.

FIG. 13 is a right side view thereof; and,

FIG. 14 is a rear view thereof.

The broken lines in the drawings depict features of the grill weight that form no part of the claimed design.

1 Claim, 10 Drawing Sheets
